UNITED STATES PATENT OFFICE.

CHARLES L. W. TRINKS, OF PITTSBURGH, PENNSYLVANIA, ASSIGNOR TO TATE-JONES & COMPANY, INC., OF PITTSBURGH, PENNSYLVANIA, A CORPORATION OF PENNSYLVANIA.

HEATING-FURNACE.

1,342,074.

Specification of Letters Patent.

Patented June 1, 1920.

Application filed August 28, 1919. Serial No. 320,504.

To all whom it may concern:

Be it known that I, CHARLES L. W. TRINKS, residing at Pittsburgh, Allegheny county, Pennsylvania, have invented a new and useful Improvement in Heating-Furnaces, of which the following is a full, clear, and exact description, reference being had to the accompanying drawings, forming part of this specification, in which—

10 Figure 1 is a front elevation of a furnace embodying my invention;

Fig. 2 is a transverse vertical section, taken on the line II—II of Fig. 3;

15 Fig. 3 is a horizontal section taken on the line III—III of Fig. 2;

Fig. 4 is a vertical section taken on the line IV—IV of Fig. 1;

Figs. 5 to 8 are detail views of the various plates constituting the inner casing;

20 Figs. 5 and 8 illustrating the bottom and top plate, respectively, while Figs. 6 and 7 illustrate the end plates.

My invention relates to heating furnaces, such as are used in forging practice. These 25 furnaces, as heretofore constructed, are both uneconomical and troublesome in their operation. They are uneconomical because the maintaining of a high furnace temperature therein causes the fluid gases to leave at 30 high temperatures so that only a very small part of the heat of combustion is utilized. They are also uneconomical because the walls must be comparatively thin, which means great heat losses by radiation. It is 35 necessary to construct furnaces with thin walls because otherwise the refractories would become overheated on the inside and would not stand up for any length of time. These furnaces are troublesome, because 40 even with the comparatively thin walls of which they are constructed, the heat distortion of the refractories causes the walls to buckle and the roofs to cave in. This requires frequent rebuilding of the furnaces.

45 My invention is designed to overcome these difficulties and to provide a furnace of this character in which the walls are so constructed as to withstand high temperatures and in which a large portion of the heat 50 which would otherwise be lost is utilized for the purpose of preheating the combustion air for the furnace.

The nature of my invention will be best 55 understood by reference to the accompanying drawings, in which I have shown a pre-

ferred embodiment thereof and which will now be described, it being premised, however, that various changes can be made in the details of construction, combination and arrangement of the various parts, without departing from the spirit and scope of my invention, as defined in the appended claims.

In these drawings, the numeral 1 designates the heating chamber of the furnace which is immediately surrounded by thin 60 refractory walls 2. These are, in turn, inclosed in a metallic casing 3, outside of which is a surrounding air space 4, adapted to carry air for combustion in the furnace in a continuous path practically entirely 65 around the furnace. The air space 4 is surrounded by a heat-insulating material 5, and this in turn is inclosed in an air-tight 70 metallic casing 6.

I am aware it is not new to provide a furnace having a double wall with an air-circulating space therein for the purpose of pre-heating air. Such furnace, however, as heretofore built, has been a failure because it is impossible to keep the refractories from 75 cracking and leaking and the maintenance cost was so excessive that the furnaces had to be abandoned. I overcome these difficulties by providing two metallic casings 3 and 6. The inner casing 3 will, of course, 80 become heated to a relatively high temperature. In fact, it may assume a dull red heat. For that reason, I use for this casing a material such as cast iron which will not readily oxidize. The outer casing will remain 85 comparatively cold so that a very light steel shell will suffice. The inner shell or casing serves a double purpose. First, its strength and rigidity acts to hold the refractory walls 2 in place, keeping them from 90 cracking and caving in; and second, it prevents leakage of combustion air into the 95 furnaces or places where such air is not wanted. The flow of the combustion air around the furnace should preferably reach 100 all wall surfaces of the air space 4, so as to leave no dead or uncooled areas. The air may be caused to take various paths. In the arrangement shown, the air enters through the bottom connection 7, as indicated by the 105 arrows, and thence flows into the air space at the right hand end of the furnace. Here the flow divides, part of the air passing upwardly through the top space and thence downwardly into the space at the front side 110

of the furnace; and part flowing laterally around the side walls and thence into the front space. To permit this flow, the plates constituting the casing 3 may be provided 5 with suitable slots, as indicated at 8.

I preferably provide the plates constituting the shell 3 with ribs 9. These ribs serve a double purpose; first they direct the flow of air so as to leave no dead spaces; and 10 second, they serve as abutments for the insulating material 5, holding the latter the proper distance from the shell or casing 3. The ribs 9 are arranged to extend in the general direction of the desired air flow.

15 In forge furnaces without a door such as I have illustrated, I preferably provide for the further preheating of the combustion air, as follows:

A suitable duct or flue 10 connects the air 20 space 4 at the left hand end of the furnace with a heating chamber 11 which is arranged at the front side of the furnace above the door. From this chamber 11 it passes by a flue or duct 12 to the burner 13. The chamber 25 11 receives heat from two sources, viz: from the interior of the furnace and through the thin inner wall 2 and also from the flame and hot gases which pass out of the door 14 and upwardly through the chimney 15. To 30 increase the heat absorption from the flame, the front wall of this chamber is provided with a plurality of ribs 16 which are directly exposed to the flame and hot gases and form an extended heat absorbing area. 35 The inner wall of this chamber also has ribs which are indicated at 17 for the purpose of increasing its heat transmitting area to the combustion air passing through said chamber. This chamber 11 is made of some 40 suitable heat resisting material such as cast iron or nichrome.

The advantages of my invention will be readily understood by those familiar with furnaces of this class since I provide a long 45 life thin-walled furnace in which the heat transmitted through the walls, and usually lost, is returned to the furnace to a large degree. My invention also provides a furnace in which the metallic shells not only act to 50 hold the refractory and heat-insulating material in place in service; but they also hold such parts during shipment and handling of the furnace, this largely preventing breakage of the refractories during such shipment 55 and handling.

I claim:

1. A heating furnace having a heating chamber inclosed by thin refractory walls, a metal casing surrounding said walls, an air 60 circulating space around the metal casing, heat-insulating material outside of said air space, and a metallic casing surrounding the heat-insulating material, substantially as described.

65 2. A high temperature heating furnace

whose walls comprise an inner refractory material, inner and outer metal casings, an air space intermediate said casing, and a heat insulator outside of the air space, substantially as described. 70

3. A high temperature heating furnace, having an inner wall of refractory material next to its heating chamber, a metal casing surrounding said wall, a space adapted for circulating combustion air, a heat insulator 75 and an outer metallic casing, substantially as described.

4. A heating furnace having a preheating duct or chamber in its wall above its door, together with means for circulating air for 80 combustion therethrough, substantially as described.

5. A heating furnace having inner and outer metallic casings, and an air duct surrounding the furnace chamber between said 85 casings, the furnace having a door and an air chamber in the furnace wall above said door, and circulating connections leading from the air space around the furnace to said chamber, and from said chamber to the 90 burner of the furnace, substantially as described.

6. A heating furnace having thin refractory walls, a metal casing around the refractory walls, an air space around said 95 metal casing in the bottom, side and roof walls, an air-preheating chamber in the furnace wall above the furnace door, and air-circulating connections leading from the air spaces in the walls to said chamber and from 100 the preheating chamber to the furnace, substantially as described.

7. A heating furnace having thin refractory walls, a metal casing surrounding said walls and having spacing ribs on its outer 105 surface, said spacing ribs being arranged to direct the flow of air along said casing, a heat-insulating material resting against said ribs, and an outer metal casing surrounding the heat-insulating material, substantially as 110 described.

8. A heating furnace having a preheating chamber around its wall above its door, said chamber being provided with external ribs extending into the path of the flame issuing from the furnace door and also having internal ribs extending in the direction of the flow of air through the chamber, substantially as described. 115

9. A heating furnace having an open door 120 and a chimney extending upwardly from the outer side of the door, an air-preheating chamber having ribs extending outwardly into the chimney, and other ribs extending inwardly across said chamber, substantially 125 as described.

In testimony whereof I have hereunto set my hand.

CHARLES L. W. TRINKS.
